UNITED STATES PATENT OFFICE.

DARIUS E. SHRAUGER, OF ATLANTIC, IOWA.

ROAD SIGN.

Application filed August 23, 1921. Serial No. 494,683.

To all whom it may concern:

Be it known that I, DARIUS E. SHRAUGER, a citizen of the United States, and resident of Atlantic, in the county of Cass and State 5 of Iowa, have invented a certain new and useful Road Sign, of which the following is a specification.

The object of my invention is to provide a combined sign board and fence post of 10 simple, durable, and inexpensive construction that may be readily, quickly and easily driven with a mallet into the ground in line with a fence and then be permanently secured to the fence wires, thereby forming 15 an additional and re-inforcing fence post for the fence, and,

My further object is to provide a sign board holder formed integral with the fence post to which a sheet metal sign board may 20 be readily, quickly and easily applied and firmly held as a permanent sign, and which holder is also provided with auxiliary sign board receiving and supporting members so arranged that temporary signs may be readily, quickly and easily applied on opposite 25 sides of the permanent sign and there firmly supported and held.

My invention consists in the construction, arrangement and combination of the various 30 parts of the sign board holder and the arrangement and combination thereof with the fence post whereby the objects contemplated are attained, as hereinafter more fully set forth, pointed out in my claims, and illustrated in the accompanying drawings, in 35 which:

Figure 1 shows a side elevation of a device embodying my invention, with part of one of the temporary sign boards broken away to 40 show the permanent sign board.

Figure 2 shows a front elevation of same.

Figure 3 shows an enlarged detail view looking downwardly upon one of the edges of the sign board and showing the permanent sign and two temporary signs in position, and

Figure 4 shows a detail perspective view illustrating one of the lower corners of a sign board holder and a portion of a permanent sign and two portions of temporary signs therein to illustrate the means for holding the sign boards in the holder.

Referring to the accompanying drawings I have used the reference numeral 10 to indicate a metal fence post of ordinary construction and preferably provided with an

anchor member 11. This fence post is preferably made of angle bar material. Near the top of the fence post is a triangular sheet metal brace member 12.

The sign holder proper is formed of angle bar material and comprises a bottom member 13 and two upright members 14, these are arranged with one flat side of the angle bar lying against the outer surface of the 65 brace plate 12 and permanently secured to the brace plate by rivets 15. Additional braces 16 of strap iron are provided and are riveted to the side members 14 and are then extended downwardly and riveted to the post 70 proper.

The device is intended to hold a permanent sheet metal sign 17 and two temporary sheet metal signs 18. I provide for holding the permanent sign in position by cutting out from the angle bar frame of the sign holder a series of lugs 19, which are bent parallel to the upright portion of the part 18 and the corresponding portion of the parts 14, thus forming a holder for the 80 sheet metal sign between said lugs 19 and the adjacent portion of the angle bar. At the top I have provided bolt openings 20 in which may be inserted bolts 21 for securing the permanent sign in position.

In order to secure the temporary signs I have provided adjacent to the lugs 19 another set of similar lugs 22 spaced outwardly from the lugs 19 so that one of the temporary signs 18 may be inserted between the 90 sets of lugs 19 and 22 as shown in Figure 4. For the other temporary sign board I have formed in the opposite member of the angle bar a series of lugs 23, those in the bottom member 13 being first extended outwardly 95 and then upwardly and those in the upright members 14 being extended first outwardly and then toward the vertical center, by this arrangement I provide from a single piece of angle bar material, what might be termed three independent receptacles for holding three signs properly spaced apart from each other.

In practical use it is obvious that by the arrangement of the sign holder relative to 105 the post and before the sign boards are put in position, the post may be driven in the ordinary way, then fence wires are secured to the post in the ordinary way making it a permanent part of the fence. The permanent sign board 17 is then slipped into the post from the top and is firmly held be-

tween a part of the angle bar and the lugs 19, then if desired it may be more firmly secured in position by the bolts 21. It is sometimes desirable to place temporary signs 5 of the sign board and when this is desired, the temporary signs may be printed on paper and pasted on flat sheet metal signs or card board signs may be employed and these are placed in the proper grooves from 10 the top of the sign board on opposite sides of the permanent sign without in any way affecting the permanent sign and without the necessity of securing the temporary sign to, or pasting it over, or in any way injuring 15 the permanent sign and then when the period of use of the temporary signs is over, they may be quickly and easily removed and the permanent sign will be unimpaired.

I claim as my invention:

20 1. An improved road sign comprising a straight post designed to be driven into the ground by blows from a mallet on the top of the post, a sign receiving frame comprising a straight horizontal bar forming the bottom, said bar being permanently fixed to one side of the post at a point spaced below the top of the post, said bar having uprights at its opposite ends, said frame thus formed being open at its top and provided 25 with sign engaging lugs, and a sign capable of being inserted in the frame from above and securely held in position by said lugs, and when thus inserted having both sides exposed.

30 35 2. A device of the class described, com-

prising a fence post, an angle bar fixed to the fence post slightly spaced apart from its top and extended horizontally with its ends extended upward and a series of lugs formed by cutting and pressing from the angle bar 40 two of said sets of lugs being arranged to coact with the adjacent part of the angle bar to form two channels for receiving two sign boards and the third set of lugs being 45 designed to coact with one of the other sets of lugs to form a channel to receive a third sign board.

3. In a device of the class described, the combination of a fence post, a triangular brace plate fixed to one side thereof, near the top a sign holder formed of an angle bar secured with its central portions to said brace plate and having a horizontal portion and upwardly extended end portions, a brace fixed to said end portions and to the post, 50 three series of lugs formed in said holder member, two sets of lugs being designed to coact with one of the sides of the angle bar holder to form two channels to receive two sign boards and the third set of lugs being 55 designed to coact with one of the other sets of lugs to form a third channel for receiving a third sign board and said parts being so arranged that all of the sign boards may be placed in their respective channels from the 60 top and will be held in the positions parallel to, but spaced apart from each other, for the purposes stated.

Des Moines, Iowa, May 27th, 1921.

DARIUS E. SHRAUGER.
